US00D810769S

(12) **United States Design Patent** (10) Patent No.: **US D810,769 S**
Zhou et al. (45) Date of Patent: **** Feb. 20, 2018**

(54) **DISPLAY SCREEN WITH GRAPHICAL USER INTERFACE**

(71) Applicant: **Shenzhen Airdrawing Technology Service Co., Ltd**, Shenzhen (CN)

(72) Inventors: **Bo Zhou**, Shenzhen (CN); **Xue-Mei Huang**, Shenzhen (CN)

(73) Assignee: **Shenzhen Airdrawing Technology Service Co., Ltd**, Shenzhen (CN)

(**) Term: **15 Years**

(21) Appl. No.: **29/568,194**

(22) Filed: **Jun. 16, 2016**

(30) **Foreign Application Priority Data**

Apr. 20, 2016 (CN) 2016 3 0133376

(57) **CLAIM**

The ornamental design for a display screen with graphical user interface, as shown and described.

DESCRIPTION

The FIGURE is a front view of an embodiment of a display screen with a graphical user interface showing our new design.

The broken line showing of the display screen is for the purpose of illustrating environment and forms no part of the claimed design. The broken lines showing of text and icons in the FIGURE illustrate portion of the graphical user interface and form no part of the claimed design.

1 Claim, 1 Drawing Sheet
